ADJUSTABLE INTERNAL EXPANSION
GRINDER

Spencer R. Keller, Handley, W. Va.

Application August 7, 1947, Serial No. 767,005

4 Claims. (Cl. 51—184.2)

1

This invention relates to internal grinding tools.

It is an object of the present invention to provide an internal grinding tool adapted for grinding the walls of cylinders or bearing surfaces which is adjustable to different diameters of the openings and wherein the grinding stones are retained against the surface being ground by the joint effect of a spring device and of centrifugal action.

Other objects of the present invention are to provide an adjustable grinder adapted for use in openings, which is of simple construction, inexpensive to manufacture, sturdy and durable, easy to adjust and efficient in operation.

For other objects and for a better understanding of the invention, reference may be had to the following detailed description taken in connection with the accompanying drawing, in which:

Fig. 1 is a side elevational view of my internal grinding tool.

Fig. 2 is an end elevational view of the tool looking upon the front of the stones.

Fig. 3 is an end elevational view of my grinding tool looking upon the spindle end of the same.

Fig. 4 is a longitudinal cross-sectional view taken on line 4—4 of Fig. 1.

Fig. 5 is an enlarged fragmentary and cross-sectional view with the grinding stones expanded to accommodate the larger diameters.

Figs. 6 and 7 are respectively transverse cross-sectional views taken respectively on lines 6—6 and 7—7 of Fig. 4.

Referring now to the figures, 10 represents a spindle adapted to fit a chuck. This spindle has an extension 11 with threads 12 thereon and a shoulder 13 against which there can be fitted a sleeve 14. This sleeve has a threaded portion 15 in which is a pin 16 extending across the opening thereof. The opening in this portion 15 is flared or tapered as shown at 17 to permit the outward pivotal movement of members 18 and 19 carrying respectively stone pieces 21 and 22. Extending beyond the threaded portion 15 of the sleeve are extensions 23 and 24 which serve to guide and confine the members 18 and 19 as they are separated or brought together. Between the ends of these extensions 23 and 24 there is extended a pin 25 which will serve to limit the inward movements of the members 18 and 19 and cause them to be kept centered. The holes in the members 18 and 19 are larger than the diameter of the pin 16 whereby to provide a loose fit and permit the members to pivot. The inner ends of the members 18 and 19 are relieved as indicated at 26 to

2

permit the members to be pivoted outwardly without interference. The outer ends of the members 18 and 19 are flared or tapered as indicated at 27 and are adapted to be engaged by the outer ends 5 of an adjusting sleeve 28 which is adjustable along the threaded portion 15 of the sleeve 14. When the adjustment has been effected, a set screw 29 is fixed to limit the further adjustment of the sleeve 28. If the sleeve 28 is adjusted rearwardly a large 10 expansion of the members 18 and 19 is permitted as shown in Fig. 5 whereby to permit larger openings to be ground.

The stone parts 21 and 22 are of half circular shape and have holes in the same for the attachment 15 of the grinding stones over projections 31 disposed respectively on the ends of the members 18 and 19. Retaining or clamping plates 32 and 33 with flanges 34 are disposed on the projections 31. The flanges 34 extending over the straight surfaces of the stone parts 21 and 22 longitudinally thereof prevent the parts from rotation on the projections independently thereof. Also disposed on the projections 31 are spring retaining elements 35 and 36 having respectively holes 37 20 for receiving a spring. These retaining elements 35 have flange portions 39 for receiving the projections. Tightening nuts 41 are disposed on the projections 31 to retain the parts tightly upon the respective members 18 and 19. The spring 38 will tend to divide the members and hold them 25 apart so that the inclined faces of the members 18 and 19 are maintained in engagement with the end of the sleeve 28.

While various changes may be made in the detail construction, it shall be understood that such changes shall be within the spirit and scope of the present invention as defined by the appended claims.

I claim:

1. An adjustable internal grinding tool comprising spindle means having a hollow threaded portion thereon, a pair of guide extensions extending from the threaded portion to serve as guides, an adjusting sleeve on the threaded portion, separable members connected to the threaded portion inwardly thereof for pivotal movement with respect thereto and extending outwardly between the guide extensions whereby to be guided in their pivotal movement as they are separated from one another, grinding stone elements disposed respectively on each of said separable members, said separable members having inclined edges adapted to be engaged by the end of the adjusting sleeve inwardly thereof, and spring means extending between said members to

force the inclined edges against the end of the sleeve whereby to retain the stone elements in their separated or adjusted positions.

2. An adjustable internal grinding tool comprising spindle means having a hollow threaded portion thereon, a pair of guide extensions extending from the threaded portion to serve as guides, an adjusting sleeve on the threaded portion, separable members connected to the threaded portion inwardly thereof for pivotal movement with respect thereto and extending outwardly between the guide extensions whereby to be guided in their pivotal movement as they are separated from one another, grinding stone elements disposed respectively on each of said separable members, said separable members having inclined edges adapted to be engaged by the end of the adjusting sleeve inwardly thereof, and spring means extending between said members to force the inclined edges against the end of the sleeve whereby to retain the stone elements in their separated or adjusted positions, said spring means comprising spring retaining elements with openings therein for receiving the ends of a coil spring, said stone retaining members comprising projections extending through the stone elements, said spring retaining elements being disposed on the projections at their outer ends and lock devices disposed respectively on the projections to fix the spring retaining members and the stones to the respective stone carrying members.

3. An adjustable internal grinding tool comprising spindle means having a hollow threaded portion thereon, a pair of guide extensions extending from the threaded portion to serve as guides, an adjusting sleeve on the threaded portion, separable members connected to the threaded portion inwardly thereof for pivotal movement with respect thereto and extending outwardly between the guide extensions whereby to be guided in their pivotal movement as they are separated from one another, grinding stone elements disposed respectively on each of said separable members, said separable members having inclined edges adapted to be engaged by the end of the adjusting sleeve inwardly thereof, and spring means extending between said members to force the inclined edges against the end of the sleeve whereby to retain the stone elements in their separated or adjusted positions, and a pin

extending between the outer ends of the extensions serving to limit the inward movement of the members which carry the stone elements and whereby to keep said members centered within the adjusting sleeve and upon their pivot connections.

4. An adjustable internal grinding tool comprising spindle means having a threaded portion thereon, an extension extending from the threaded portion to serve as guides, an adjusting sleeve on the threaded portion, separable members connected to the threaded portion for pivotal movement with respect thereto and extending outwardly between the guide extensions whereby to be guided in their pivotal movement as they are separated from one another, grinding stone elements disposed respectively on each of said separable members, said separable members having inclined edges adapted to be engaged by the end of the adjusting sleeve, and spring means extending between said members to force the inclined edges against the end of the sleeve whereby to retain the stone elements in their separated or adjusted positions, said members having projections for receiving the stone elements, clamping plates adapted to be extended over the projections and having lips extending along their bottom edges to fit flush with the sides of the stone elements whereby to keep the stones from turning on the projections when the clamping plates and the stone are tightened thereupon.
